WILLIAM KOCH, OF LOS ANGELES, CALIFORNIA

AUTOMATIC DOOR CONTROL

Application filed June 21, 1927. Serial No. 200,448.

As will be inferred from the above title, my invention relates to automatic door controls, and more particularly to a type that is hydraulic in action.

5 It is an object of my invention to provide an automatic door control for garage doors or the like, operable from a point remote from said garage, the operating mechanism being preferably positioned so as to obviate the necessity of alighting from the automobile (which is particularly disagreeable in inclement weather) to unlock and open or close garage doors before driving in.

10 It is also an object of my invention to provide positive locking means inside the garage or the like, the same being so positioned as to render the mechanism incapable of being tampered with from the outside.

15 These and other objects of my invention will be apparent from a consideration of the specification and the accompanying drawings, in which:

20 Fig. 1 is a top plan view of my device, the walls of a garage or its equivalent being broken away;

25 Fig. 2 is a perspective view showing the piping arrangement of the operating mechanism;

30 Fig. 3 is a longitudinal section through the cylinder, taken as indicated in line 3—3 of Fig. 1;

35 Fig. 4 is a fragmentary sectional view, comparable to a portion of Fig. 3, showing a locking device in closed or locked position.

Fig. 5 is a section taken on line 5—5 of Fig. 2, showing in elevation the operating levers and the locking arrangement therefor.

40 Referring to the specific embodiment of my invention shown in the drawings, and the details thereof, 11 may be a power cylinder supported upon a longitudinal track 12, as by U-bolts 13 and 13'. The track 12 is hung longitudinally in the center of the garage indicated at 14, and is supported at its forward end by the cross member 15, and at the rear end by brackets 15' depending from the ceiling of said garage.

45 The power cylinder 11 may be provided with pistons 16 and 16' mounted upon a piston rod 17. Said piston rod may extend for-

wardly through a packing gland 18, and the extreme forward end of said piston rod is connected with a carriage 19 by means of a pin and slot connection 20. Said carriage may also be adapted to pivotally support the rear ends of door opening levers 21 and 22, while the forward ends of said levers make pivotal connection with garage doors 23 and 24, respectively.

55 At the rear end of the power cylinder 11 I may connect, as by an elbow 25, an opening power line 26, and at a point forward of the pistons 16 and 16', preferably in a casting 27 which may have threaded connection with the power cylinder 11, I may connect 60 a closing power line 28, as by a threaded connection indicated at 29. The power lines 26 and 28 may be readily carried to any convenient point, preferably under-ground, and may be connected to the operating mechanism as and for the purpose hereinafter described.

65 Describing now the more unique features of my invention, I may provide a latching means embodying a spring strip 10 mounted on the top of the casting 27 by means of bolt 9. The forward end of the strip 10 may be bent to provide a hook 30 adapted to engage a latch member 31 mounted on the carriage 19, when said carriage having been motivated by the pistons 16 and 16' through the piston rod 17, has reached its extreme inward position, at such time the doors being closed and latched.

70 75 80 85 90 95 100 Mounted upon the piston rod 17 is a cam 32 adapted to engage the hook 30 at the initial forward movement of the rod 17 and to disengage said hook 30 from latching member 31. The continued forward movement of the piston rod 17 will, after the unlatching operation force open the garage doors 23 and 24 through the medium of the levers 21 and 22. The slot 20 in rod 17 permits a slight movement of rod 17 prior to the movement of carriage 19 and member 31, thus permitting the disengagement of latch 30 from the member 31. The member 32 is beveled at both ends so that it is also operative in a door closing operation, in which case the hook 30

rides upon the cam and is held there until the member 31 moves past the hook.

For the operating mechanism I may provide a series of inter-connected pipes and valves, somewhat as shown in Fig. 2, in which 5 33 may be a lead from the water supply main or its equivalent, valved as at 34, the lead 33 and valve 34 making a connection with one of a pair of three-way valves 35 and 36. A 10 branch 37 from the lead 33 may provide a source of water power for the valve 35. Connected also to the valves 35 and 36 are pipes 38 and 38' which may be a continuation of the opening and closing power lines 26 and 15 28, respectively. On opposite sides of the valves 35 and 36 I may provide drain pipes 39 and 39', respectively, which are inter-connected as by a T 40 to the main drain 41.

Operating levers 42 and 42' adapted to 20 open and close their respective valves 35 and 36 may be positioned relatively so as to provide simple and rugged locking means, as shown at 43 in Fig. 5, in which are shown webs 44 and 44' cast integral with the operating levers 42 and 42', respectively, and co-operating to provide by means of an opening 45, means for inserting the hasp of a padlock 46.

The control mechanism is housed in a casting C positioned at the side of the driveway 30 in advance of the garage so as to be accessible to a driver of a car.

In the operation of my device, it will be clearly understood that the driver of an 35 automobile upon approaching the operating mechanism positioned at the side of the driveway, can conveniently without alighting from the automobile insert a key in the lock 46, and by moving for instance the lever 42' to such a position as to allow water 40 from the main 33 to pass through the valve 36 into the pipes 38 and 26 into the power cylinder 11, thus forcing the pistons 16 and 16' to a forward position, causing the unlatching of the member 31 and the consequent forward movement of the garage 19 45 for opening the doors of the garage.

When the doors have completely opened, the driver after having returned the lever 50 42' to its original closed position, thereby allowing the water to drain from the power cylinder 11 back through the pipe 26 and 38 through the valve 36 into the drain 39, may proceed to drive into the garage.

To close the garage doors the driver, after 55 having left the machine in the garage may return past the operating mechanism, which may be advantageously located close to the entrance of the house, and by the movement 60 of the lever 42 open the valve 35, allowing water from the main 33 to pass into the pipe 38 on through the inter-connecting pipe 28 to the power cylinder 11 forward of the pistons 16 and 16', forcing said plungers rearwardly for closing the doors 23 and 24, in-

identally accomplishing the latching or locking thereof.

Although I have herein described but one complete embodiment of my invention, it will be understood that various features 70 might be changed and numerous additions might be made without departing from the spirit and scope of my invention as referred to above and in the appended claims.

What I claim is:

1. An opening and closing mechanism for a pair of doors, including a hydraulic cylinder stationarily mounted with respect thereto, a piston in said cylinder operatively connected with and adapted to open and close said doors, and having a rod extended therefrom, a carriage connected with said rod, a latch member on said carriage, a control mechanism mounted at a point remote from the doors and including separate opening and closing valves connected respectively with said cylinder on opposite sides of said piston for conducting a pressure fluid to the cylinder in a door opening and closing operation, means connected with said valves for selectively feeding the pressure fluid thereto and for draining the same therefrom, and a latch bar projecting longitudinally from an end of said cylinder and operable at the completion of a door closing operation for 90 engaging said latch member to latch and hold the doors closed, and further operable at the initiation of an opening operation for unlatching the doors, and means movable with said piston and adapted to be engaged by said latch.

2. An opening and closing mechanism for a pair of doors including a hydraulic cylinder stationarily mounted with respect thereto, 105 a piston in said cylinder operably connected with and for opening and closing said doors and having a rod extended from the cylinder, a carriage associated with said rod, a control mechanism including separate opening and closing valves connected respectively with said cylinder on opposite sides of said piston for conducting a pressure fluid to the cylinder in door opening and closing operations, means connected with said valves for selectively feeding the pressure fluid thereto and for draining the same therefrom, 115 a locking device including a latch bar on said cylinder, means on said carriage engageable with said latch bar for locking the doors in closed position, and means on said rod for engagement with said latch bar at the completion of a closing operation and at the initiation of an opening operation for unlatching and unlatching said doors respectively.

3. A door opening and closing mechanism including a hydraulic cylinder, a piston reciprocably mounted therein, a rod connected with said piston and extended from said cylinder, a track adjacent said cylinder, a car- 130

riage movable over said track, doors connected with said rod and said carriage, the connection between said rod and said carriage being arranged to permit a slight movement of the carriage independently of the rod, a latch carried on said cylinder and overlying said rod, a latch engaging member on said carriage, and means on said rod engaging said latch for latching and unlatching the carriage against and to permit the movement of the doors, respectively.
